UNITED STATES PATENT OFFICE

138,177

DESIGN FOR A SET OF PLAYING CARDS OR SIMILAR ARTICLE

Allen Field, New York, N. Y.

Application March 1, 1944, Serial No. 112,754

Term of patent 3½ years

(Cl. D34—13)

To all whom it may concern:

Be it known that Allen Field, a citizen of the United States of America and resident of the city of New York, State of New York, has invented a new, original and ornamental Design for a Set of Playing Cards or Similar Article, of which the following is a specification, reference being had to the accompanying drawings forming part thereof, in which the drawings are plan views of a set of playing cards, showing my new design.

The opposite sides of the cards (not shown) are blank.

I claim:

The ornamental design for a set of playing cards or similar article, substantially as shown and described.

ALLEN FIELD.
